UNITED STATES PATENT OFFICE.

AUGUST SEIFERT, OF BROOKLYN, NEW YORK, ASSIGNOR TO ROBERT GAIR COMPANY, OF BROOKLYN, NEW YORK, A CORPORATION OF NEW YORK.

COUNTER CARTON.

Application filed April 22, 1920. Serial No. 375,758.

To all whom it may concern:

Be it known that I, AUGUST SEIFERT, a citizen of the United States, residing in Brooklyn, in the county of Kings and State 5 of New York, have invented certain new and useful Improvements in Counter Cartons, of which the following is a specification.

My present invention relates to an improvement in counter cartons for receiving, 10 shipping, displaying and advertising goods therein.

One of the objects of my device is to provide a carton or container of the class described, which may be made from a single blank, and by reason of being so made, will permit a greater economy in the printing of the display surface thereof, inasmuch as it is desirable, in some instances, so to locate the display portion of said carton as to receive advertisements or pictorial illustrations upon one side of the device only, although both sides of the display container may be so printed in the more expensive type 20 of containers or cartons.

Another important object of my device is the provision of means whereby the carton may be locked in carton form quickly and economically without the use of glued-up 30 joints.

Another important object of my device is the provision of means in connection with a cover whereby the carton may be tilted when placed upon the counter for more 35 readily exposing the goods to inspection.

These and other capabilities will be ascertained from a further reading of the following specification.

In the accompanying drawings, 40 Figure 1, shows the carton in closed position.

Figure 2, shows the device opened and in tilted display position.

Figure 2^a, is an end view of the device 45 opened and in tilted display position.

Fig. 3, shows the blank from which the device is formed.

Fig. 4, discloses the same bent up or folded upon the scorings and cuts.

50 Fig. 5, shows the device in partially folded assembled position.

Fig. 6, shows the same in position for

operating to extend the rest or easel portion of the device for the display position as shown in Fig. 2.

Similar letters or numerals denote similar parts throughout the several views.

My device is made of cardboard or other suitable material and preferably is blanked out of a single sheet of the material. Reference being had more particularly to Fig. 4, my device comprises an interior bottom portion 10, an exterior bottom portion 11 foldably connected to the interior bottom portion 10, for receiving the interior bottom portion therein, and a cover 12 foldably connected to the exterior bottom portion 11.

The interior bottom portion 10 is provided with a rectangular bottom 13, somewhat wider than long, having side-extensions 14 and 15, and end-extensions 16 and 17. These side-extensions and end-extensions are foldably connected to the bottom 13 along the side and end lines thereof, but are not connected to each other at the corners 70 of the bottom 13, and are arranged to turn up at right-angles to the bottom 13, by bending or folding along the lines of connection to the bottom 13.

The exterior bottom portion 11 is provided with a bottom 18, of substantially the same shape and size as the bottom 13, having a side-extension 19, and end-extensions 20 and 21. The side-extension 19, which in shape and size is substantially the same 80 as the side-extensions 14 and 15 of the bottom 13, is foldably connected to the side-extension 14 and is foldably connected to the bottom 18, along the longitudinal lines of the bottom 18 and the side-extension 14, 85 and is arranged to turn up at right angles to the bottom 18 by bending or folding along the line of connection to the bottom 18.

The end-extensions 20 and 21 are foldably connected to the bottom 18 along the end lines of the bottom 18, and are substantially of the same size and shape as the end-extensions 16 and 17 of the bottom 13, and are arranged to turn up at right angles to the bottom 18, by bending or folding along the line of connection to the bottom.

The end-extensions 20 and 21 are provided with freely-hanging end pieces 22 and 23,

connected thereto and foldable at right angles to the end-extensions 20 and 21, the purpose of the freely-hanging end pieces being hereinafter stated.

- 5 The end-extensions 20 and 21 are provided, at the ends opposite to the freely-hanging end pieces 22 and 23, with cooperating lock-tabs or latches 24, 24' which are shown in Figs. 3 and 4, the lock-tabs or latches 24 and 24' being foldably connected at one end to the end-extensions 20 and 21, and having at the other ends interlocking recesses or notches 25, 25'. In width the lock-tabs or latches 24 are the same as the height or width of the end-extensions 20 and 21, and the lock-tabs or latches are arranged to be turned at right angles to the end-extensions 20 and 21 by bending or folding along the lines of connection to 20 and 21.

10 The cover 12 comprises the covering portion 26 which is connected to the easel brace 27 by the outer side and easel back portion 28, the covering portion 26 having the flap 29.

15 The easel brace 27 normally forms part of the exterior bottom 18, and is four sided, having an upper longitudinal line 30 and a lower longitudinal line 31 which is shorter than the upper line, the lines 30 and 31 being connected by side lines 32 and 33 converging to the lower line 31, the easel brace at the lower line 31 being foldably connected to the bottom 18, and its side lines 32 and 33 being free or detached from the bottom 18.

20 The outer side and easel back portion 28 is substantially the same shape and size as the side-extension 15 of the bottom 13. The outer side and easel back portion 28 is foldably connected along its lower longitudinal line to the easel brace 27 and is foldably connected along its upper longitudinal line to the covering portion 26. The outer side and easel back portion 28 is provided with a triangular or other suitably formed detent or tilt-lock 34 foldably connected on one of its sides to the outer side and easel back portion 28 and free or detached therefrom on its other sides, the purpose of the detent or tilt-lock being hereinafter mentioned.

25 The covering portion 26 corresponds substantially in shape and size to the shape and size of the bottom 13 of the interior bottom portion 10 and is foldable as along the line 35 for the purpose hereinafter mentioned.

30 The flap 29 is foldably connected along its lower or inner longitudinal line to the covering portion 26, and in length is substantially the same as the length of the bottom 13 of the interior bottom portion 10, and in height or width is substantially the same as the side extension 15. The outer ends of

35 the flap 29 may be trimmed or rounded as at 36, for convenience in operating the flap.

40 To arrange the parts in relation for forming the carton or box, again referring to Fig. 4, the interior bottom portion 10 is turned upwardly on the foldable lines between the side-extensions 14 and 19 and is received in the exterior bottom portion 11, as shown in Fig. 5, with the freely-hanging end pieces 22 and 23 folded or bent at right angles to the end extensions 20 and 21 and engaging the side-extensions 14 and 19 between the latter extensions. The carton or box is thus provided with a double bottom of which the exterior bottom portion 11 forms the outer bottom. The side-extensions 14 and 19 being adjacent to each other, thus form double sides for the carton or box, the side-extension 19 forming the outer one of these double sides. The inner side-extension 15 being adjacent to the outer side and easel back portion 28 of the cover 12, thus forms double sides for the carbon or box opposite to the first mentioned double sides, the intermediate portion 28 being the outer of these sides. The end-extensions 16 and 20 and 17 and 21 being adjacent to each other thus form opposite double ends for the carton or box, the end-extensions 20 and 21 forming the outer of these ends. The freely-hanging end-pieces 22 and 23, being in engagement with and between the side-extensions 14 and 19 press outwardly against the side-extension 19, and thus provide pressure or tension members for holding the interior bottom portion 10 in place in the exterior bottom portion 11.

45 The recesses or notches 25, 25' of the lock-tabs or latches 24, 24' are brought into interlocking engagement with each other on the outer side of the rear of the container and thus lock the parts together, the recessed or notched ends of the lock-tabs or latches preferably being engaged on the under sides of the lock-tabs or latches, as shown in Figs. 1 and 6, to protect the recessed or notched ends from injury. The flap 29 is then tucked into the box or carton by folding down the cover 12 and bending the flap 29 until the flap is in engagement with the adjacent face of the side-extension 14, the pressure due to the flexibility of the cover holding the cover in place.

50 To provide an easel back or rest for the carton or box for purposes of display, the easel brace 27 and the outer side and easel back portion 28 are drawn outwardly and downwardly, as indicated by the arrow, to form a projection or rest 37, Figs. 2 and 2^a, the covering portion 26 being drawn down to the line 35 to form a temporary outer side for the carton or box, the tilt-lock 34 is bent outwardly to engage the upper edge thereof with the lower edge of the lock-tabs or latches 24, the lock-tabs or latches being

in locking engagement, the detent or tilt-lock 34 thus preventing collapsing or return of the easel brace 27 and outer side and easel back 28 to normal operative position 5 in the carton or box. The flap 29 of the cover is then bent along the line of its attachment to the cover 26 sufficiently to cause the cover to stand at such angle as may be desired to display effectively printed or 10 other matter arranged on the cover and flap.

It will be noted that the end-pieces 22 and 23 and the locking-tabs or latches 24, when the carton or box is in assembled form, aid in strengthening the sides or longer portions 15 of the carton or box in addition to performing the tension and locking functions hereinbefore stated.

In practice the outer and inner bottoms and outer and inner sides and ends may be 20 of the same respective dimensions, and the inner members be readily received in operative relation within the confines of the outer members when in operative relation, due to the "give" or flexibility of the material 25 of which the carton or box preferably is made.

Referring to Fig. 3, which shows the blank by which my carton or box is formed, the dotted lines denote scored lines upon the 30 cardboard or material of which the blank consists, and the full lines within the confines of Fig. 3 denote the cut lines to form members which tend to retain or lock the carton or box in assembled form.

35 The blank from which the carton or box is formed by folding the blank on the scorings and cuts thereof, comprises the main portion A rectangular in shape, in length about three times its width, and having end 40 extensions B and C and side extensions D and E.

The main portion A comprises the inner bottom section 13, the inner side section 14, the exterior bottom section 18 having the 45 easel brace section 27, the outer side section 19, the outer side and easel back section 28 having the tilt lock section 34, and the covering section 26.

The end extension B comprises the cover 50 flap section 29, and the end extension C comprises the inner side section 15.

The side extension D comprises the inner end section 16, the outer end section 20, the free hanging end-piece section 22, and 55 the locking tab section 24 having the locking notch 25.

The side extension E comprises the inner end section 17, the outer end section 21, the free hanging end-piece section 23, and 60 the locking tab section 24' having the locking notch 25'.

The inner bottom section 13 is defined from the inner side sections 14 and 15 by 65 the transverse scorings 36 and 37, and is defined from the inner end sections by the

longitudinal scorings 38 and 39. The exterior bottom section 18 is defined from the outer side section 19 and the outer side and easel back section 28 by the transverse scorings 40 and 30, and from the outer end sections 20 and 21 by the longitudinal scorings 42 and 43.

The outer side section 19 is defined from the inner side section 14 by the transverse scoring 44. The outer end sections 20 and 21 are defined from the free hanging end-piece sections 22 and 23 by extensions of the scoring 40 and from the locking tabs 24 and 24' by extensions of the scoring 30. The free hanging end-piece sections 22 and 23 are separated from the inner and outer side sections 14 and 19 by the longitudinal cuts 45 and 46 and from the inner end sections 16 and 17 by the transverse cuts 47 and 48. The easel brace section 27 is defined from the exterior bottom section 18 by the transverse scoring 31 and is separated therefrom on two of its sides by the cuts 32 and 33 diverging from the scoring 31. The locking tab sections 24 and 24' are defined from the outer end sections 20 and 21 by extensions of the scoring 30, and are separated from the outer side and easel back section 28 and the covering section 26 by the longitudinal cuts 52 and 53. The outer side and easel back section 28 is defined from the covering section 26 by the transverse scoring 54, and is provided with the tilt lock 34 separated therefrom by the cuts 55 and 56 and foldable on the short longitudinal scoring 57.

The covering section 26 has thereon the transverse scoring 35 for defining the temporary or false outer side section, for the carton or box when the same is in display position and for folding the covering section 26 thereon when the same is in display position. The covering section is defined from the cover flap section 29 by the transverse scoring 58, and is separated from the locking tab sections 24 and 24' by said cuts 52 and 53.

The carton blank is made from a single sheet or piece of material of rectangular form, and is made with a minimum wastage of material, the wastage only arising at the upper ends of the blank, and therefore making for greater economy in the manufacture of cartons or boxes of the described type.

To form the blank into a carton, the procedure is as follows: The blank lying in front of the operator extended as in Fig. 3, the inner side section 15 is folded downwardly along the scoring 37 and the inner end forming sections 16 and 17 are folded downwardly along the scorings 38 and 39, this being permitted by the cuts 47 and 48. The outer and inner side forming sections 14 and 19 are folded downwardly along the scoring 36. The outer end forming sections 130

20 and 21 are folded upwardly along the scorings 42 and 43; the end-piece sections 22 and 23 are folded upwardly along the scoring 40 and turned inwardly towards each other, the cuts 45, 46, 47 and 48 permitting this. The outer and inner side forming sections 14 and 19 are folded upwardly along the scoring 40 and carried over the inwardly turned end-pieces, the inner bottom 13 thus being received in the outer bottom 18. The outer side and easel back section 28 is folded upwardly along the scoring 30, the formation of the rectangular receptacle or body of the carton thus being completed. The locking tab extensions 24 and 24' are folded upwardly along the scoring 30 and turned inwardly towards each other, the cuts 52 and 53 permitting this, and are interlocked by means of the locking ends 25 and 25', thus retaining the carton in assembled form. The cover section 26 is folded upwardly along the scoring 54 and the flap 29 is folded downwardly on the scoring 58 and tucked into the receptacle portion of the carton.

26 Having thus described my invention it should be understood that there may be modifications thereof and variations therein without departing from the spirit of the invention or exceeding the scope of the appended claims.

Having thus described my invention, I claim:

1. In a container formed by folding, the combination of, an outer bottom; an inner bottom receivable in the outer bottom; sides and ends for the outer and inner bottoms; the sides and ends of the outer bottom providing outer sides and outer ends for the container and the sides and ends of the inner bottom providing inner sides and inner ends for the container; means for locking said outer and inner sides and outer and inner ends in operative relation in the container; and a covering portion for the container; the outer bottom having an easel brace portion connected to one of said outer sides; said easel brace portion and the outer side connected thereto being movable to provide an easel brace and an easel back for supporting the container in display position.

2. In a container formed by folding, the combination of, an outer bottom; an inner bottom receivable in the outer bottom; sides and ends for the outer and inner bottoms; the sides and ends of the outer bottom providing outer sides and outer ends for the container and the sides and ends of the inner bottom providing inner sides and inner ends for the container; means for locking said outer and inner sides and outer and inner ends in operative relation in the container; and a covering portion for the container; the outer bottom having an easel brace portion connected to one of said outer sides; said easel brace portion and the outer

side connected thereto being movable to provide an easel brace and an easel back for supporting the container in display position; and the covering portion being movable to provide a temporary outer side for the container when the container is in display position.

3. In a container formed by folding, the combination of, an outer bottom; an inner bottom receivable in the outer bottom; sides and ends for the outer and inner bottoms; the sides and ends of the outer bottom providing outer sides and outer ends for the container and the sides and ends of the inner bottom providing sides and inner ends for the container; means for locking said outer and inner sides and outer and inner ends in operative relation in the container; and a covering portion for the container; the outer bottom having an easel brace portion connected to one of said outer sides; said easel brace portion and the outer side connected thereto being movable to provide an easel brace and easel back for supporting the container in display position; the covering portion being movable to provide a temporary outer side for the container when the container is in display position and provide a display tab for the container.

4. In a container formed by folding, the combination of, an outer bottom; an inner bottom receivable in the outer bottom; sides and ends for the outer and inner bottoms; the sides and ends of the outer bottom providing outer sides and outer ends for the container and the sides and ends of the inner bottom providing inner sides and inner ends for the container; means for locking said outer and inner sides and outer and inner ends in operative relation in the container; and a covering portion for the container; the outer bottom having an easel brace portion connected to one of said outer sides; said easel brace portion and the outer side connected thereto being movable to provide an easel brace and an easel back for supporting the container in display position; said outer side having means for retaining the easel brace portion and the outer side in said supporting position.

5. In a container formed by folding, the combination of, an outer bottom; an inner bottom receivable in the outer bottom; sides and ends for the outer and inner bottoms; the sides and ends of the outer bottom providing outer sides and outer ends for the container and the sides and ends of the inner bottom providing inner sides and inner ends for the container; means for locking said outer and inner sides and outer and inner ends in operative relation in the container; and a covering portion for the container; the outer bottom having an easel brace portion separated therefrom by cuts through the outer bottom on two opposed sides of

- said portion and respectively connected at its other opposed sides to the outer bottom and to one of said outer sides; said easel brace portion and the outer side connected thereto being movable to provide an easel brace and an easel back for supporting the container in display position; the outer side connected to the easel brace portion having a tilt lock for retaining the easel brace portion and said outer side in supporting position; the covering portion being movable to provide a temporary outer side for the container when the container is in display position and a display tab for the container.
6. A blank of suitable material having scoring and cuts for folding the blank thereon to form a container, the blank comprising, an inner bottom section; side sections and end sections for the inner bottom section; an outer bottom section; side sections and end sections for the outer bottom section; free hanging end-piece sections; an easel brace section comprised in the outer bottom section and foldably connected to one of the side sections of the outer bottom section; said side section of the outer bottom section providing an easel back for cooperating with the easel brace section; locking tabs; and a covering section having a cover flap.
7. A blank of suitable material having scoring and cuts for folding the blank thereon to form a container, the blank having a rectangular main portion and end extensions and side extensions; the main portion comprising an inner bottom section, a side section for the inner bottom section, an outer bottom section, side sections for the outer bottom section, an easel brace section comprised in the outer bottom section and connected to one of the side sections of the outer bottom section, said side section of the outer bottom section providing an easel back for cooperating with the easel brace
- section, and a covering section, the covering section being movable for providing a temporary outer side for the container when in display position; the end extensions respectively comprising a flap section for the covering section, and a side section for the inner bottom section; the side extensions comprising end sections for the inner bottom section, free hanging end-piece sections, end sections for the outer bottom section, and locking tab sections.
8. A blank of suitable material having scoring and cuts for folding the blank thereon to form a container, the blank having a rectangular main portion and end extensions and side extensions; the main portion comprising an inner bottom section, a side section for the inner bottom section, an outer bottom section, side sections for the outer bottom section, an easel brace section comprised in the outer bottom section and connected to one of the side sections of the outer bottom section, said side section of the outer bottom section providing an easel back for cooperating with the easel brace section and having means for retaining the easel brace section and easel back section in cooperating relation for supporting the container in display position, and a covering section, the covering section being movable for providing a temporary outer side for the container when in display position; the end extensions respectively comprising a flap section for the covering section and a side section for the inner bottom section; the side extensions comprising end sections for the inner bottom section, free hanging end-piece sections, end sections for the outer bottom section, and locking tab sections.

AUGUST SEIFERT.
